UNITED STATES PATENT OFFICE.

FRED H. DANIELS, OF WORCESTER, MASSACHUSETTS.

RAIL-BOND FOR ELECTRIC RAILWAYS.

SPECIFICATION forming part of Letters Patent No. 626,980, dated June 13, 1899.

Application filed April 25, 1899. Serial No. 714,395. (No-model.)

To all whom it may concern:

Be it known that I, FRED II. DANIELS, a citizen of the United States, and a resident of Worcester, in the county of Worcester and State of Massachusetts, have invented a certain new and useful Improvement in the Manufacture of Rail-Bonds for Electric Railways and other Purposes, of which the following is a specification.

My invention has reference to a rail-bond designed more particularly for use as a connection between the terminals of the two adjoining rails of an electric railway, and consisting of strands of copper wire twisted together in the flattened copper-wire rope or cable, as shown, for example, in Figure 2 of the drawings of my Patent No. 582,849, of May 18, 1897. In making such bonds it has been found when the rope or cable is flattened that the wires of which it is composed are bruised and indented one into the other, and in some instances nearly or quite cut through by the pressure requisite to flatten the rope, while the conducting power of the bond as a whole is materially impaired. I have discovered that this defect can be obviated entirely by omitting from the interior of the cable several of the strands, depending in number upon the cross-section of the cable and the number of strands of wire composing it, the cable in effect being tubular or pipe-like instead of solid throughout, as heretofore has been the case. When this tubular or pipe-like cable is flattened, the wire strands under the pressure, to which they are subjected have the opportunity, owing to the space afforded for this purpose by the tubular structure of the unflattened cable, to adjust themselves to their new position and in their new relations without any injury to themselves or without cutting or bruising one another, the resulting product being in this respect noticeably different from the flattened bond made from or

ordinary copper-wire cable, and, moreover, being much more flexible and satisfactory in every way than the latter.

In the accompanying drawings, Fig. 1 is a view of a section of the tubular or pipe-like copper-wire cable or rope from which the connector or bond is to be made. Fig. 2 is a cross-section of the same. Fig. 3 is a view of the bond after it has been flattened out between its ends. Fig. 4 is a cross-section of the same through the flattened part.

The copper-wire rope or cable is shown at A, Fig. 1. The difference between it and the ordinary copper-wire rope is that several of the central or core wires—in this instance seven—are omitted, thus giving to the rope a tubular or pipe-like structure. This tubular rope is shown in Fig. 2 as flattened, with the exception of its ends. These ends themselves can be secured or welded by pressure to suitable terminals in the manner set forth in my aforesaid patent, No. 582,849.

Having described my improvement, what I claim, and desire to secure by Letters Patent, is—

1. The improvement in the manufacture of rail bonds or connectors for electric railways which consists in forming from strands of copper wire a tubular rope or cable, and then flattening said rope or cable by pressure, substantially as and for the purposes hereinbefore set forth.

2. As an improved article of manufacture, a rail-bond made from tubular flattened copper-wire rope or cable, as hereinbefore set forth.

In testimony whereof I have hereunto set my hand this 21st day of April, 1899.

FRED II. DANIELS.
